UNITED STATES PATENT OFFICE.

SAMUEL P. BUSH, OF COLUMBUS, OHIO.

DRAFT AND BUFFING APPARATUS.

No. 857,827.

Specification of Letters Patent.

Patented June 18, 1907.

Application filed May 11, 1906. Serial No. 316,408.

To all whom it may concern:

Be it known that I, SAMUEL P. BUSH, a resident of Columbus, in the county of Franklin and State of Ohio, have invented 5 certain new and useful Improvements in Draft and Buffing Apparatus; and I do hereby declare the following to be a full, clear, and exact description of the invention, such as will enable others skilled in the art to 10 to which it appertains to make and use the same.

My invention relates to an improved draft and buffing apparatus, the object of the invention being to provide improvements of 15 this character comprising few and simple parts, which shall be easy and cheap to construct, strong and durable in use, universal in application and very accessible.

A further object is to provide an improved 20 draft and buffing apparatus which will be direct in action and be superior to indirect wedge acting friction devices such as heretofore known, and having a small reaction is superior to strictly spring devices, at the 25 same time having all the facilities for modifying or absorbing shocks between cars, as possessed by either or both the ordinary spring and friction devices.

With these and other objects in view, the 30 invention consists in certain novel features of construction and combinations and arrangements of parts as will be more fully hereinafter described and pointed out in the claims.

In the accompanying drawings, Figure 1 is 35 a view in side elevation with draft iron removed, illustrating my improvements. Fig. 2 is a view in cross section on the line $x-x$ thereof. Fig. 3 is a view in cross section through the followers, and Figs. 4 and 5 are 40 views of a modification. Figs. 6 and 7 are views showing the positions of the parts at different stages during the buffing action.

1 represents the butt end of a car coupling, to which the yoke strap 2 is secured in any 45 approved manner.

3, 3 represent the parallel draft irons having carrying irons 4, 4, secured thereto, forming supports for the yoke 2 and followers, as will be hereinafter pointed out.

5 and 6 represent a pair of pivoted or fulcrumed followers located at the forward end of the yoke, a similar pair being located at the rear end of the yoke, the rear follower 5 bearing against the rear end of the yoke 2, 55 and the forward follower 5 bearing against the butt end of the coupling. The inner fol-

lowers 6 are made with lugs 7 projecting into the ends of a coiled spring 8, and the pairs of followers 5 and 6 having frictional engagement with each other. The engaging faces 60 of the followers 5 and 6 are made with V-shaped grooves to increase the friction and the wearing surface of the followers against each other.

Each of the followers 5, 6 is made with 65 lateral trunnions 10 at their lower ends and these trunnions are disposed between lugs or enlargements 11 on the carrying irons and flanges or bearings 14 at the lower edges of the draft irons 3. As clearly shown in Fig. 70 1, the trunnions 10 of the followers 6 are normally spaced from the lugs or enlargements 11 against which they subsequently abut, to allow a certain free movement of the followers against the tension of the spring before 75 any frictional movement of the followers against each other takes place. This is desirable to cushion light jars and strains.

The draft irons 3 are provided with shoulders 12 to be struck by the followers 6 and 80 limit their movement.

The operation of the device is as follows:— The followers of one set move for the forward action or pull and the other set take the buffing strains. Normally the trunnions on followers 5 will rest against the lugs 11 under them, and the trunnions on the followers 6 will bear upwardly against the bearings 14, as shown in Fig. 1. In the buffing action, the draw bar of the coupling pressing against the 85 follower 5, will first move the followers 5 and 6 at this end of the yoke, back horizontally to the position shown in Fig. 6 to effect a preliminary movement of the spring. When the trunnions 10 on follower 6 contact with 90 the lugs 11 behind them, and the trunnions on the follower 5 contact with the bearings 14 above them, subsequent rearward movement of the draw bar will cause the upper ends of the followers to move through different 95 arcs as the followers turn on the bearings 11 and 14 which are spaced apart, and the contacting faces of the followers will move against each other. The resistance of the spring (the rear end of which bears against 100 the then stationary rear follower), will create friction between the moving followers until the follower 6 contacts with the shoulders 12 on the draft irons, at which time they will be disposed at approximately the same angle as 105 the rear followers, as shown in Fig. 7. On being released, the followers will be returned 110

to normal positions, by the action of the spring. In the initial part of the movement, the contact of the follower 5 with coupling 1 and the follower 6 with the spring are maintained in line with the center of the coupling. As the buffing movement increases, the point of contact of the follower 5 with the coupling, will move rearwardly toward the fulcrum of the latter on the bearings 14, and the point of contact of the spring with the follower 6 will move rearwardly away from the fulcrum of the latter on the lugs 11. This arrangement allows the movements of the spring to be made greater than the movement of the coupling and results in a largely increased resistance to the action of the coupling toward the end of the movement.

The contacting surfaces of the followers, which may or may not be V-shaped, may consist of a number of friction pieces 13, movably locked in recesses in the wearing faces of the followers as shown in Figs. 4 and 5; or in one of each pair of followers. These loose pieces are in the nature of inserts set loosely in cavities or housings in the face of the followers, so that the surfaces, whether they be flat or V-shaped may adjust themselves readily, one to the other, that is to say those that contact with each other. But as the followers move and the contacting surfaces slide with relation to each other in opposite directions, these pieces will be restricted or not permitted to get out of position by reason of the confines of the cavity in which they are set in the follower, but by having some little latitude within this cavity on account of the separation, the surfaces can adjust themselves more readily to each other and get a more perfect contact.

Various slight changes might be resorted to in the relative arrangement of parts shown and described without departing from the spirit and scope of my invention hence I would have it understood that I do not wish to limit myself to the exact construction of parts shown and described, but,

Having fully described my invention what I claim as new and desire to secure by Letters-Patent, is:—

- 50 1. The combination of contacting friction elements movable simultaneously and having pivotal mountings located in proximity to each other, and a resisting spring pressing against said elements.
- 55 2. The combination of contacting friction elements movable together in the same plane, means for imparting a subsequent pivotal movement to said elements whereby they will be moved relatively to each other and a spring pressing against said friction elements.
- 60 3. The combination of two contacting friction elements, means affording pivotal mountings for the lower ends of said friction elements and a spring pressing against said friction elements.

4. The combination of a draw bar, a yoke and draft irons, of a friction element bearing against the draw bar, a second friction element contacting with the first mentioned friction element, a spring bearing against the second friction element and means for permitting said elements to turn on pivotal supports located below the same and supported by the draft irons.

5. The combination of two contacting friction elements normally disposed in an inclined position, means under said elements affording pivotal mountings therefor and a spring pressing one friction element toward the other.

6. The combination with two contacting friction elements normally disposed in an inclined position, pivotal mountings for said elements, said mountings being spaced apart and permitting an initial simultaneous movement of said elements and a subsequent pivotal movement, and a spring pressing one element against the other.

7. In a friction draft and buffing apparatus, the combination of two sets of fulcrumed contacting friction elements, and an intermediate resisting spring between them.

8. In a friction draft and buffing apparatus, the combination of contacting friction elements having fixed fulcrums, and a resisting spring bearing against the said friction elements.

9. In a friction draft and buffing apparatus, the combination with a yoke, of two sets of friction elements, pivotal bearings for each of said friction elements fixed to a part stationary with respect to the yoke and friction elements and a resisting spring between said friction elements.

10. In a friction draft and buffing apparatus, the combination of fulcrumed friction elements, each element having a series of beveled faces contacting with the other friction element, and a resisting spring bearing against said friction elements.

11. In a friction draft and buffing apparatus, the combination of friction elements having a series of beveled contacting faces, fixed fulcrums for the friction elements, and a resisting spring bearing against the elements.

12. In a friction draft and buffing apparatus, the combination of two sets of friction elements each set having a series of beveled faces between them, fixed pivots for the friction elements, and a resisting spring between them.

13. In a draft and buffing apparatus, the combination of contacting friction elements having simultaneous movement, the contacting faces moving in opposite directions relatively to each other, fixed pivotal mountings for said elements and a resisting spring bearing against said friction elements.

14. In a draft and buffing apparatus, the

combination of pivoted or fulcrumed friction elements, an actuating device contacting with one element, a spring pressing against the other element, said points of contact being so located relatively to the fulcrums of the elements as to increase the movement transmitted to the spring beyond that of the actuating device.

15 In a draft and buffing apparatus, the combination of pivoted or fulcrumed friction elements constructed and mounted so as to have a preliminary longitudinal movement before pivoting, and a resisting spring bearing against the friction elements.

16 In a draft and buffing apparatus, the combination of two sets of pivoted or fulcrumed friction elements having a preliminary longitudinal movement before pivoting, and a resisting spring between the pairs of friction elements.

17. In a draft and buffing apparatus, the combination with a coupler, draft irons and a yoke secured thereto, of a pair of friction elements at both ends of the yoke one pair bearing against the coupler and the other against

the end of the yoke, a coiled spring supported on lugs on the inner friction elements, and fixed pivots or fulcrums for all of said friction elements, supported by the draft irons.

18. In a draft and buffing apparatus, the combination with a coupler, and a yoke secured thereto, of a pair of friction elements at both ends of the yoke, a spring between the pairs of friction elements, draft irons having shoulders to limit the movement of the friction elements, and carrying irons providing pivots or fulcrums for the friction elements.

19. In a draft and buffing apparatus, the combination of fulcrumed elements, friction devices on the opposing faces of said elements, said devices having beveled faces, and a spring bearing against the elements.

In testimony whereof, I have signed this specification in the presence of two subscribing witnesses.

SAMUEL P. BUSH.
